CLAIM

The ornamental design for a spherical section finger brace, as shown and described.

DESCRIPTION

FIG. 1 is a perspective view showing my new design for a spherical section finger brace shown in condition of use;
 FIG. 2 is a bottom plan view;
 FIG. 3 is a front elevational view;
 FIG. 4 is a top plan view;
 FIG. 5 is a left side elevational view which is a mirror image of the right side;
 FIG. 6 is a rear elevational view;
 FIG. 7 is a bottom perspective view; and,
 FIG. 8 is a top perspective view.

The broken lines showing a hand and straps illustrate environmental structure and form no part of the claimed design.
